CLAIM

The ornamental design for a pouring spout for paint pot, as shown and described.

DESCRIPTION

FIG. 1 is a perspective of a pouring spout for paint pot showing my new design. The broken line showing of a paint pot is for illustrative purposes only and forms no part of the claimed design;

FIG. 2 is a top view thereof; and,

FIG. 3 is a bottom view thereof.

The opposite side of that shown in FIG. 1 is plain and unornamented.
